LAPPING OR HONING

Raymond H. Cramer, Newark, N. J., assignor to
General Motors Corporation, Detroit, Mich., a
corporation of Delaware

Application May 16, 1939, Serial No. 273,947

8 Claims. (Cl. 51—26)

This invention relates to lapping or honing and comprises all of the features and aspects of novelty herein disclosed. Objects of the invention are to provide an improved method and an improved apparatus for lapping or honing races, especially tapered, spherical or otherwise contoured raceways of antifriction bearings. Another object is to provide a lapping or honing apparatus wherein the lap has the contour of the raceway and is pressed against it while relative movement of rotation and of oscillation occur simultaneously. To these ends and also to improve generally upon devices of this character, the invention consists in the various matters hereinafter described and claimed.

In the drawings,

Fig. 1 is a vertical sectional view of a lapping machine with some parts in elevation.

Fig. 2 is a similar view of a portion of a modified apparatus.

Fig. 3 is an elevation, with some parts in section, of another modification.

Fig. 4 is an elevation, with some parts in section, of still another modification.

Fig. 5 is chiefly a side elevation of Fig. 4.

Fig. 6 is a plan view of a bearing having caged lapping rollers.

Fig. 7 is a diametrical section of Fig. 6.

Figs. 8 and 9 are sectional views of other bearings.

Fig. 10 is a sectional view of the bearing of Fig. 7 with the inner race and honing device in another position.

Fig. 11 is a plan view of a lapping device.

Fig. 12 is a sectional view of Fig. 11.

Fig. 13 is a plan view of a modified lapping device.

Fig. 14 is a sectional view of Fig. 13.

Fig. 15 is a sectional view of the lap of Fig. 13 in lapping relation to a bearing.

In Fig. 1, a frame member 10 is provided with bearings for a vertical shaft 12 which is supported and rotated in any suitable way, as by a pulley. The upper end of the shaft is recessed and tapped to receive a screw stud 13 projecting downwardly from a work support 14 provided with a circumferential centering flange 16. Fastened by screws to the support 14 is a friction ring 18 upon which rests the thicker end of an outer race ring 20 of a self-aligning bearing of the barrel roller type, for example. The raceway is a spherical segment and is engaged by barrel rollers 22 spaced apart in a circular series by a cage 24. The rollers engage and conform to a raceway on an inner race 26. The rollers can be the rollers intended for the bearing or special lapping rollers and they can be replaced by a split lapping device or a shoe type of lap as will appear.

The upper end of the inner race ring engages a friction ring 28 fastened by screws to a flange

30 on a pulley hub 32, there being a centering projection 34 entering the bore of the inner race ring. The hub is rotated by a pulley 36 having a driving belt 38. A selected weight 40 is attached to or forms a part of the pulley and the connected parts form a pressure member which presses the inner race ring into the lapping rollers or other lapping device with the desired lapping pressure. The weight is attached to a shaft 42 suitably journaled for rotation and swivelled to a piston rod projecting out of a cylinder 44 which is secured on a standard 46. The piston rod is actuated to lift the weighted pulley or pressure member in order that the work may be inserted and removed. Lapping compound may be supplied gradually or the parts may be submerged therein. A spatter guard 50 surrounds the rotating parts. The inner and the outer race rings can be rotated at the same or different speeds and preferably in opposite directions. If desired, the driving of one race ring, especially the inner race ring, can be dispensed with. The caged lapping rollers are free to rotate on their individual axes and to revolve as a unit.

In the modification of Fig. 2, the lapping rollers 58 are free to rotate on their axes in slots of a ring 60 but the ring is held from revolution by being pinned to a flanged sleeve 62 which is bolted to the frame.

30 In the modification of Fig. 3, the weighted pulley or pressure member has an extension 70 provided with a conical seat for a ball 72 which also engages a conical seat 74 placed off-center or eccentric to an extension 76 on a driven pulley 78 which rotates on a fixed vertical axis. The ball 72 acts as a crank to oscillate the weighted pulley 36 around an axis 80 which is the center of curvature of the outer raceway. The axis of the pressure member travels in the surface of a cone 40 whose apex is at 80. The inner race ring 26 and the lapping rollers 22 also oscillate around the axis 80. Thus the lapping rollers or any substituted lapping devices not only move circumferentially with respect to the outer raceway but they also oscillate or move transversely of the outer raceway.

Figs. 4 and 5 illustrate another mechanism for oscillating the inner race ring and the lapping device. The flange 30 is formed on a shaft 82 which is journaled in bearings carried by an oscillated sleeve 84 having arms 86 pivoted upon trunnions 88. The trunnions 88 are in line with the center 80 of race curvature and are supported by lugs 90 projecting from a standard 92. The sleeve 84 has a lug pivoted at 94 to a link 96 which is also pivoted on a crank pin 98 which is eccentric to a driven belt pulley 100 which rotates on a fixed axis. The crank and the link effect oscillation of the sleeve 84 and the parts 50 supported thereby and the inner race ring will

oscillate around the center 88 as it rotates. Various oscillating speeds can be selected as by changing the pulley. Rotation is imparted to shaft 82 by a weighted pulley 102 having a headed projection 104 normally swinging idly in a slot 106 of a member 108 carried by a piston rod 110 projecting from a lifting cylinder 112. The weighted pulley or pressure member is lifted to facilitate insertion or removal of work, the shaft 82 being slideable in the sleeve 84. The fixed axis of oscillation provided by the trunnions 88 is perpendicular to the axis of shaft 82 and to the axis of rotation of the outer race ring.

Figs. 6 and 7 illustrate a self-aligning bearing having an outer race ring, an inner race ring and cagedlapping rollers. The arrows indicate directions of rotation. The speeds can be different and rotation of one race ring can be dispensed with. Fig. 8 indicates a taper roller bearing capable of being lapped by the mechanisms shown in Figs. 1 and 2. Fig. 9 shows another type of self-aligning bearing capable of being lapped by the mechanisms shown in Figs. 1 to 5. Fig. 10 indicates a bearing similar to that of Figs. 4 and 5 with the inner race ring and roller lap in one of the tipped positions. In the case of Fig. 9 the inner race ring alone will be oscillated by the mechanisms of Figs. 3, 4 and 5 and such ring will wipe along the roller laps as it oscillates.

Figs. 11 and 12 show a split type lap comprising a ring split as at 120. The internal surface 122 conforms to the contour of the inner race ring of Fig. 10 and is slotted radially at a number of points as at 124. The external surface 126 conforms to the contour of the outer raceway and is slotted radially at a number of points as at 128. Such a lap is springy and yielding and can be substituted for the roller lap of Figs. 1 to 5.

Figs. 13, 14, and 15 show a shoe type lap comprising a ring 130 with a series of internal radial recesses 132 to receive and guide shoes 134, each shoe being urged inwardly by a coil spring 136 surrounding a stud 138 on the ring 130. The inner surfaces of the shoes conform to the contour of the inner raceway of Fig. 10. The ring 130 also has a series of external radial recesses 140 to receive and guide shoes 142, each shoe being urged outwardly by a coil spring 144 surrounding a stud 146. The shoes 142 conform to the contour of the outer raceway. Cast iron, brass or abrasive are suitable materials for the lapping device.

I claim:

1. The method of lapping the contoured raceways of inner and outer self-aligning bearing rings of different diameters, which consists in interposing a contoured lapping device in the annular space between the raceways, rotating at least one of the race rings upon its axis, pressing one of the race rings towards the other to create pressure between the lapping device and the raceways, and oscillating one of the race rings around a fixed axis at the center of curvature of one of the raceways; substantially as described.

2. The method of lapping the contoured inner and outer raceways of self-aligning bearing rings, which consists in interposing a contoured lapping device in the annular space between the raceways, rotating at least one of the race rings upon its axis, pressing one of the race rings towards the other to create pressure between the lapping device and the raceways, and swinging the lapping device and one race ring as a unit around the center of curvature of the raceway on the other race ring; substantially as described.

3. In a machine for lapping the contoured raceways of bearing race rings of different diameters, means for supporting and rotating the outer race ring upon its axis, means for supporting and rotating the inner race ring upon its axis, a lapping device pressed between the raceways and conforming to them, and means for causing relative oscillation around another axis between one of the race rings on the one hand and the other race ring and the lapping device on the other hand, said other axis being perpendicular to the axis of said other race ring; substantially as described.

4. In a machine for lapping the contoured raceway of a bearing race ring, means for supporting and rotating the race ring upon its axis, a lapping device comprising a circular series of lapping elements spaced apart circumferentially of the race ring and conforming to the raceway, means for pressing the lapping device against the raceway, and means for causing relative oscillation between the lapping device and the race ring around a fixed axis passing through the center of curvature of the raceway, said fixed axis being perpendicular to the race ring axis and intersecting the latter; substantially as described.

5. In a machine for lapping the contoured raceway of a bearing race ring, a rotary support for the race ring, a lapping device comprising a series of individually rotatable lapping rollers engaging the raceway, a pressure member for urging the lapping device against the raceway, and a crank for oscillating the pressure member around a fixed axis passing through the center of curvature of the raceway at right angles to the race ring axis; substantially as described.

6. In a machine for lapping the raceway of a bearing race ring, a support for the race ring, a lapping device engaging the raceway, a pressure member for urging the lapping device against the raceway, means for rotating the pressure member around its axis, a driving pulley out of line with said axis, and a belt offset with respect to the pulley and connecting the pulley and the pressure member to cause the pressure member to change its axis of rotation; substantially as described.

7. In a machine for lapping the raceway of a bearing race ring, a support for the race ring, a lapping device engaging the raceway, a pressure member for urging the lapping device against the raceway, means for rotating the pressure member around its axis to cause the lapping device to travel circumferentially of the raceway, a sleeve rotatably supporting the pressure member, and means for oscillating the sleeve back and forth about a fixed axis to cause the lapping device to oscillate crosswise of the raceway while partaking of said circumferential travel; substantially as described.

8. In a machine for lapping the raceway of a bearing race ring, a rotary support for the race ring, a lapping device engaging the raceway, a pressure member for urging the lapping device against the raceway, means for rotating the pressure member around its axis to cause the lapping device to travel circumferentially of the raceway, a sleeve rotatably and slidably supporting the pressure member, and a device for shifting the pressure member axially with respect to the sleeve for sliding movement toward or from the race ring to provide space for removal or insertion of the lapping device therebetween; substantially as described.

RAYMOND H. CRAMER.
